RAZOR BLADE SHARPENING ATTACHMENT

Application filed May 4, 1932. Serial No. 609,223.

The present invention has in view a device to facilitate the sharpening of safety razor blades by reciprocating movement of the blades on a concave surface.

5 An object of the invention is the provision of an attachment for a safety razor blade which is adapted to be applied thereto when the blade is to be sharpened for spacing the body of the blade from a concave 10 sharpening surface so that the beveled edges of the blades are evenly positioned against the said surface.

To obtain the best results in the sharpening of razor blades, it is essential that the 15 beveled edges of the blades be presented evenly and at the proper angle against the honing surface. When the blade is so positioned, movement of the same back and forth over the honing surface will produce a keen 20 cutting edge. The present invention, therefore, contemplates the use of a concave surface as the sharpening surface and a device adapted to be applied to the body of the blade which spaces the central portion of the 25 blade the required distance from the sharpening surface, so that the bevelled edges of the blade are arranged against the sharpening surface at an angle which will produce a keen edge.

30 Another object of the invention is the provision of an attachment of this character which is adapted to be applied to the blade by engagement with the longitudinal slot thereof, and so constructed that it may be 35 readily applied to the said blade and removed therefrom after the blade is sharpened.

With these and other objects in view, 40 the invention resides in the novel features of construction and arrangement of parts which will be more fully described and claimed hereinafter.

The invention is illustrated in the accompanying drawing, in which

Figure 1 is a perspective view of a safety razor blade and an attachment affixed thereto shown in position to be sharpened in a drinking glass or tumbler;

50 Fig. 2 is a cross sectional view of a safety

razor blade and the attachment therefor on a section of a tumbler;

Fig. 3 is a perspective view of a safety razor blade and below the blade the attachment in position to be applied thereto;

Fig. 4 is a cross sectional view of a safety razor blade and the attachment in position thereon.

The invention comprises an attachment 10 adapted to be applied to a safety razor 60 blade 11 of the type having two oppositely-arranged longitudinal cutting edges and a longitudinal opening or slot 12 arranged centrally of the blade for the purpose of applying it to a razor blade holder. To 65 sharpen a blade of such construction, the invention contemplates the use of a concave sharpening surface, such as provided by the inner surface of a drinking glass or tumbler 13. It is not the intention, however, to confine the invention to the use of a tumbler or 70 drinking glass as the sharpening surface, as any device with a smooth concave surface may be used for such purpose.

In order to position the blade on the concave surface so that by reciprocating movement thereof the edges will become sharpened, the attachment 10 is provided, which spaces the body of the blade from the sharpening surface the required distance so 75 that the bevelled edges of the blade are presented evenly against the said surface and at the proper angle thereto. The said attachment may be made of any suitable material 80 which is capable of being flexed when applying it to the blade and which will return to its normal form when in position thereon, it having been found that relatively stiff cardboard is suitable for such purpose. The 85 said attachment is preferably formed from a single piece of material which is folded to the required form and which, as shown in the drawing, includes a bottom fold 14 and oppositely-arranged accordion folds 15 and 16 forming a continuation of the longitudinal edges of the said fold 14. Constructed in this manner, the attachment 10 is 90 adapted to be applied to the blade by flexing the folds 15 and 16 to an upstanding position as shown in Figure 3, in which posi- 95 100

- tion the upper layers of the folds may be passed through the slot 12 of the blade and then permitted to assume their normal, folded condition, thus attaching the blade there-
 5 to as shown in Figure 4. When applied to the blade, the said attachment has an equal number of folds arranged on each side thereof and this construction provides the same spacing of the blade from the sharpening
 10 surface for each side thereof, it being understood that after the blade is moved back and forth on the said surface with one side in contact therewith, it will be turned over and moved back and forth with the other side in
 15 contact therewith. 70
- When it is found necessary to sharpen a safety razor blade of the type hereinbefore described the attachment 10 may be applied thereto, and the blade with the attachment
 20 is placed in position on an arcuate honing surface such as the interior surface of a tumbler, as shown in Figure 1, and a finger of the operator pressed against the top of the attachment, as shown in dotted outline
 25 in Figure 2, to cause the opposite face of the attachment to contact with the honing surface and the edges of the blades to be brought into proper registry with the said surface, to provide a keen cutting edge by
 30 movement of the blade thereover. 80
- Having described my invention, I now claim:
1. An attachment for a safety razor blade for spacing the central portion of the blade from an arcuate honing surface the required distance to position the edges of the blade in proper relation to the said surface, to provide keen cutting edges by movement thereover, said attachment comprising an in-
 35 tegral piece of flexible material folded to form a bottom ply, and a plurality of accordian folded plies forming a continuation of each of the longitudinal edges of said bottom ply, said attachment being narrower
 40 than the width of said blade, and when applied to said razor blade having an equal number of said plies arranged on each side thereof for spacing the said razor blade
 45 equi-distant from the outer surfaces of the
 50 said attachment. 85
  2. A device of the character described comprising a strip of flexible material folded to form a bottom ply of rectangular shape, and a plurality of superimposed accordian folded plies forming a continuation of each of the longitudinal edges of the said bottom
 55 ply, said accordian folded plies being rectangular in shape and less than half the
 60 width of the said bottom ply. 90
  3. A honing attachment for safety razor blades which are provided with a centrally disposed slot or opening, said attachment comprising spacing members adapted to be
 65 disposed on opposite sides of the blade, and
 70 a connecting member passing through the slot or opening of the blade, one of said spacing members being collapsible to permit its passage through the slot or opening. 75
